UNITED STATES PATENT OFFICE

HENRY J. BRINKER, OF WHITAKER, AND CHARLES MCINTYRE, OF SHARON,
PENNSYLVANIA

RAT TRAP

Application filed February 5, 1931. Serial No. 513,491.

The invention relates to rat traps and important objects thereof are to provide a rat trap, of the character described, which will function to automatically reset itself by the 5 operation of parts thereof actuated by the movement of rats confined therein, which is simple in its construction and arrangement, durable and efficient in its use, positive in its action and comparatively inexpensive to 10 manufacture.

With the foregoing and other objects in view which will appear as the description proceeds, the invention resides in the combination and arrangement of parts and in the 15 details of construction hereinafter described and claimed, it being understood that changes in the precise embodiment of the invention hereinafter disclosed can be made within the scope of what is claimed without departing 20 from the spirit of the invention.

In the drawing wherein like numerals of reference designate corresponding parts throughout the several views:—

Figure 1 is top plan view of a rat trap, 25 constructed in accordance with the invention, with the cover in the open position.

Figure 2 is a sectional view on line 2—2, Figure 1.

Figure 3 is a top plan view of the lower section of the device.

Figures 4 and 5 are, respectively, side and rear end views of an improved rat trap.

Referring in detail to the drawing 1 and 2, respectively denote upper and lower casings, 35 which are preferably constructed from sheet metal, and rectangular in contour. The upper casing 1 is mounted and supported on top of, and extends partially into the open upper end of the lower casing 2, and may be removed from the latter when required.

The lower casing 2 comprises the pair of side walls 3 and 4, a rear end wall 5, a bottom 6 and a front end wall 7. The front end portion 8, of the bottom 6, is disposed above the 45 plane of the latter to provide an angularly extending entrance opening 9 therebetween, adjacent to the forward end of the lower casing 2.

An entrance door 10, is pivotally mounted, 50 centrally of its length, in the lower casing 2,

by means of a transversely extending shaft 12, which is carried by the side walls 3 and 4, and disposed directly rearward of the rear end of the bottom portion 8 constituting the front wall of the entrance opening 9.

The entrance door 10 carries a weight 10' at the rear end thereof for overbalancing and tilting the door 10 for normally maintaining the latter in the closed position.

When the entrance door 10 is in the closed 60 position, the rear end thereof rests in an angle bar 11, which extends transversely on the bottom 6 directly rearward of the rear end of the entrance opening 9. Such engagement of the entrance door 10 in the angle bar 11 prevents the rats from possibly actuating the entrance door 10 to effect their escape through the entrance opening 9.

A longitudinally extending trip bar 13 is mounted in the lower casing 2, and is pivotally connected, as at 14, adjacent to its rear end, to the side wall 3. The trip bar 13 is provided with a notched front end 15, which is adapted for engaging the rear end of the entrance door 10 to maintain the latter in the open position, as shown in Figure 2.

A trip plate 16 is mounted in the lower casing 2 adjacent to the rear end wall 5. The trip plate 16 is pivotally connected in position by a shaft 17, which extends transversely through the lower casing 2 and is supported by the side walls 3 and 4 adjacent to the bottom 5. A link 18 provides a pivotal connection between the front end of the trip plate 16 and the rear end of the trip bar 13.

A weight 19 is carried at the rear end of the trip plate 16 for overbalancing the latter toward its rear end. The rear end of the trip plate 16 is provided with a depending flange 20 to limit and determine the downward movement of the rear overbalanced end of the trip plate 16 prior to the resetting operation in a manner to be described.

A bait holder 21 is secured in the lower casing 2 adjacent to the rear end of the latter and directly above the rear end of the trip plate 16.

The upper casing 1 virtually constitutes a closure member for lower casing 2, and comprises a pair of side walls 22 and 23, a bot-

tom 24, a pair of ends walls 25 and 26 and a top cover 27. The latter is secured to the top of the side wall 22 by hinges 28, and is adapted to be secured in closed position to the top of the side wall 23 by means of latching elements 29.

The front end of the bottom 24, of the upper casing 2, is provided with a large opening 30, which permits the rats to enter the upper casing 1 from the lower casing 2 and which further provides clearance for the front end of the entrance door 10 when the latter is tilted in the closed position, as clearly shown in dash lines in Figure 2.

15 A trap door 31 is mounted in the upper casing 1 directly rearward of the bottom opening 30, and has its upper end pivotally connected to the side walls 22 and 23, by a shaft 32. The trap door 31 is gravity operated and normally extends at an angle with the free end thereof disposed rearwardly. A lip 31' is stamped upward from the bottom 24 directly rearward of the free end of the trap door 31. The lip 31' is provided to eliminate the possibility of the rats actuating the trap door 31 to return through the latter after having once entered the upper casing 1.

20 A gate 33, fixed to a shaft 34, is mounted in the upper casing 1 adjacent to the rear end of the latter. The shaft 34 extends transversely and has its ends journaled in respective side walls 22 and 23 at the top of the latter.

25 A lever 35, mounted and longitudinally shiftable on the shaft 34 is provided for shifting the gate 33 to the horizontal position against the under side of the cover 27, as shown in Figures 1 and 2; and for shifting the said gate 33 to the vertical position, as shown in dash lines in Figure 2. A lock nut 36 is mounted on the end of the shaft 34, and is adjustable against the lever 35 for securing the gate 33 in the horizontal or vertical position.

30 The side wall 4, of the lower casing 2, and the cover of the upper casing 1, are preferably provided with wire mesh panels, respectively indicated at 37 and 38, to allow the inspection of the interior of respective casings 1 and 2.

35 The rear end wall 26, of the upper casing 1 is provided with perforations 39 to permit draining of water from said casing 1, when the latter is employed for drowning captured rats.

40 The side walls 22 and 23 of the upper casing 1, are preferably formed with perforations 40 which are positioned forward of the drop door 34 to allow the entrance of light through the opening 30, for enticing the rats from the lower casing to the upper casing 1.

45 A vertically disposed flange 41 is fixed to the underside of the upper casing bottom 24. The flange 41 is positioned adjacent to the rear end of the entrance door 10, and is spaced

from the said door 10 when the latter is in the open position, so as not to catch the tails of the rats when the door 10 is moving to the open position, in the manner to be described.

70 Assuming that all parts of the device are in the positions shown in Figure 2, the operation of the present invention is as follows:— The entrance door 10 is first set in the open position by engaging the rear end thereof in the front notched end 15 of the trip bar 13, and placing bait in the holder 21. The rat can now enter through the entrance opening 9, and travels rearwardly in the lower casing 2 until it steps upon the front end of the trip plate 16, depressing said front end and thereby causing the trip bar 13 to release the entrance door 10. The latter will fall to the closed position, as shown in dash lines in Figure 2. The rat being trapped in the lower casing 2 will leap upon the now closed entrance door 10, toward the bottom opening 30, thereby actuating the said entrance door 10 to reengage the front notched end 15 of the trip bar 13. The entrance door 10 is now again ready for the reception of the next rat. The captured rat leaps through the bottom aperture 30 into the upper casing 1 and through the trap door 31. The latter will fall by gravity to the closed position trapping the rat in the upper casing 1.

80 To destroy the captured rats, the latter are forced to the rear end of the upper casing 1 by shifting and securing the gate 33 in the vertical position, as shown in dash lines, in Figure 2. The rats are now confined in the rear end of the upper casing 1 and the latter is removed from the top of the lower casing 2 and has its rear end immersed in water until the captured rats are drowned, after which 90 they are removed by opening the cover 27.

85 The present invention provides an efficient device of its kind, which will function automatically to reset itself, until the trap is filled to its capacity.

95 What we claim is:

1. In a rat trap, a casing provided with an entrance opening, an entrance door for said opening pivotally mounted in said casing, a trip plate pivotally mounted in said casing, a trip bar having a pivotal connection in said casing and with said trip plate, said trip bar having a notched end engaging said entrance door for holding the latter in the open position, the depression of said trip plate actuating said trip bar to release said entrance door to allow the latter to shift to the closed position.

100 2. In a rat trap, a casing provided with an entrance opening, an entrance door for said opening pivotally mounted in said casing, said entrance door being gravity operated for shifting to the closed position, a trip plate pivotally mounted in said casing, a trip bar having a pivotal connection in said casing

and with said trip plate, said trip bar having a notched end engaging said entrance door for holding the latter in the open position, the depression of said trip plate actuating said trip bar for releasing said entrance door.

3. In a rat trap, a casing provided with an entrance opening, an entrance door for said opening pivotally mounted in said casing, said entrance door being gravity operated for shifting to the closed position, a trip plate pivotally mounted in said casing, a trip bar having a pivotal connection in said casing and with said trip plate, said trip bar having a notched end engaging said entrance door for holding the latter in the open position, the depression of said trip plate actuating said trip bar for releasing said entrance door, said entrance door being automatically engaged and held in the open position by the notched end of said trip bar when said entrance door is shifted to the open position.

4. In a rat trap, a casing provided with an entrance opening, an entrance door for said opening pivotally mounted in said casing, a trip plate pivotally mounted in said casing, a trip bar having a pivotal connection in said casing and with said trip plate, said trip bar having a notched end engaging said entrance door for holding the latter in the open position, the depression of said trip plate actuating said trip bar to release said entrance door to allow the latter to shift to the closed position, said door being automatically engaged and held in the open position by the notched end of said trip bar when said entrance door is shifted to the opening position.

5. In combination, a rat trap comprising a lower casing provided with an entrance opening, an upper casing removably mounted on the top of said lower casing, an entrance door for said entrance opening pivotally mounted in the forward end of said lower casing, said entrance door extending horizontally when in the open position, an opening in the upper casing disposed directly over the front end of said entrance door, a trip plate pivotally mounted in the rear end of said lower casing, a trip bar pivotally connected with said lower casing and with said trip plate, said trip bar having a notched forward end for engaging the rear end of said entrance door, for holding the latter in the open position, a weight carried by the rear end of said entrance door for automatically shifting the latter to the closed position when released from said trip bar, the depression of said trip plate actuating said trip bar for releasing said entrance door the rear end of said entrance door being automatically engaged and held by the notched end of said trip bar when said entrance door is shifted to the open position, and a trap door pivotally mounted in said upper casing and disposed adjacent to the

opening in the latter and operable for returning to the closed position by gravity.

6. In combination, a rat trap comprising a lower casing provided with an entrance opening, an upper casing removably mounted on the top of said lower casing, an entrance door for said entrance opening pivotally mounted in the forward end of said lower casing, said entrance door extending horizontally when in the open position, an opening in the upper casing disposed directly over the front end of said entrance door, a trip plate pivotally mounted in the rear end of said lower casing, a trip bar pivotally connected with said lower casing and with said trip plate, said trip bar having a notched forward end for engaging the rear end of said entrance door for holding the latter in the open position, a weight carried by the rear end of said entrance door for automatically shifting the latter to the closed position when released from said trip bar, the depression of said trip plate actuating said trip bar for releasing said entrance door, the rear end of said entrance door being automatically engaged and held by the notched end of said trip bar when said entrance door is shifted to the open position, a trap door pivotally mounted in said upper casing and disposed adjacent to the opening in the latter and operable for returning to the closed position by gravity, and a gate pivotally mounted in said upper casing and shiftable for disposing same in a horizontal or vertical direction in the latter.

In testimony whereof we affix our signatures.

HENRY J. BRINKER.
